UNITED STATES PATENT OFFICE.

AUGUSTINE FRANK LITTLEFIELD, OF LYNN, MASSACHUSETTS, ASSIGNOR TO UNITED SHOE MACHINERY CORPORATION, OF PATERSON, NEW JERSEY, A CORPORATION OF NEW JERSEY.

TRIMMING MACHINE.

Application filed December 6, 1919. Serial No. 342,969.

To all whom it may concern:

Be it known that I, AUGUSTINE F. LITTLEFIELD, a citizen of the United States, and resident of Lynn, in the county of Essex and State of Massachusetts, have invented 5 certain Improvements in Trimming Machines, of which the following description, in connection with the accompanying drawings, is a specification, like reference characters on the drawings indicating like parts in the several figures.

This invention relates to cutting machines and is herein illustrated as embodied in a machine for trimming surplus material 15 from the bottom of a shoe.

In the manufacture of canvas shoes of the "sneaker" type it is customary to lay an insole on the bottom of a last and then place an upper on the last and bend the 20 lower margin thereof over upon the margin of the insole. This lasting operation causes puckers in the bent-over margin of the upper particularly at the toe portion of the shoe. Puckers are also liable to form at the 25 shank portion or elsewhere but not to the same extent as at the toe portion. Aside from this surplus material in puckered form, other surplus material is sometimes present at the shank portion where the vamp 30 and quarter overlap. It is desirable that all surplus material of whatever nature be removed as far as practicable so as to provide an even surface to receive the rubber sole since slight projections, which would 35 produce no undesirable appearance on the bottom of a leather sole will be imparted readily to a rubber sole because of its plastic, flexible nature.

Machines for removing the surplus upper 40 material which projects from the bottom of the toe portion of a lasted McKay shoe have hitherto been of the type shown in the patent to Ashton No. 891,130 in which a rotary milling cutter is used, or of the type 45 shown in the patent to McFeely No. 1,054,656, in which a coarse abrading member is employed. Such machines operate satisfactorily upon leather shoes but are not suitable for use upon shoes in which the 50 upper material, by which the lining is meant to be included, comprises rubber or rubberized fabric or fabric which is more or less impregnated with rubber cement. When such shoes are presented to machines

like those of the patents, the tools tear the 55 material of the upper and rapidly become clogged with the rubber content. With Goodyear welt and turned shoes the surplus material at the toe as well as that along the entire inseam has commonly been 60 trimmed off by so called inseam trimming machines the operation being begun at about the heel breast line and continued progressively along the inseam, the lip or shoulder 65 of the insole or sole serving as a guide. Such machines are not suitable for use with 70 shoes of the sneaker type in which there is no lip or shoulder.

According to one feature of the present 75 invention there is provided cutting means 70 adapted to extend substantially across the shoe so as to be capable of engaging surplus material on opposite sides of the shoe, means for operating the cutting means to produce a draw cut and means for directing 80 the toe portion of the shoe in position to cause the surplus material to be severed. In the illustrative mechanism, a rotary 85 disk-like knife of concavo-convex form is employed, the knife edge being kept moist by means of a wet wick held in contact with it, and a guide engages the bottom of the shoe and directs the shoe, toe foremost, to the knife in position to cause the surplus material to be severed first at the extreme 90 toe portion and then simultaneously at opposite sides of the toe portion. With this mechanism the operation is a rapid one and leaves the overlasted margin of the upper 95 smooth.

According to another feature of the invention a machine is provided by which not only the surplus material at the toe portion but any which may occur at the shank or sides of the bottom of the shoe may be 100 removed. In the illustrative machine two rotary concavo-convex knives are mounted in proximity to each other in such relation that a lasted shoe may be readily presented first to one and then to the other, one knife being mounted on a shaft which is inclined at such an angle that the lasted shoe may be presented toe-foremost to it, and the other knife being mounted on a substantially upright-shaft to facilitate presentation of the shoe sidewise. By presenting the shoe first to one and then to the other of the knives, all the objectionable surplus ma- 105

material may readily be removed. And in order to permit this removal to be accomplished readily and accurately, work guides and gages of improved construction are provided to co-operate with the knives.

These and other features of the invention will be described as embodied in an illustrative machine and pointed out in the appended claims.

10 Referring to the accompanying drawings,

Fig. 1 is a side elevation of a machine in which the present invention is embodied;

Fig. 2 is a front elevation of the machine;

15 Fig. 3 is a view, principally in elevation, showing a piece of work about to be presented to the knife for removing surplus material from the toe portion of the shoe;

20 Fig. 4 is a perspective showing more particularly the means for limiting the depth of cut of the knife which is shown in Fig. 3;

Fig. 5 is a section showing the piece of work being presented to the knife which removes surplus material from the shank portion of the shoe, and

25 Fig. 6 is a perspective of a lasted shoe after it has been operated upon at the toe portion and at one side of the shank portion.

The illustrative machine comprises two 30 rotary disk-like concavo-convex knives 7 and 9, the former being designed to remove surplus upper material from the bottom of the toe portion of a lasted shoe and the latter being adapted to remove surplus material from the side portions of the bottom 35 of the shoe and particularly from the shank thereof. Referring more particularly to Fig. 1, a driving shaft 11 has mounted upon it fast and loose pulleys 13 and 15 from one to the other of which a driving belt 17 may

40 be moved by means of a belt shifter 19 by manipulating a handle 21 at the end of an arm 23, said arm being pivoted at 25 to the frame of the machine and having a pin 27 which passes through a slot formed in the shifter 19. Fast to the driving shaft 11 is

45 a pulley having three steps 29, 31, 33. The rotary knife 7 is driven from the step 29 by a belt 35 which passes around the step 29, around two idler pulleys one of which is shown at 37, and around a pulley 39 which is fast to the shaft 41. This shaft is mounted at an angle of about 45°; and the knife 7 fast to its lower end has its concave side facing downward. The other 50 knife 9 is driven from the step 31 by a belt 43 which passes around the step, over the idler pulleys 45 and around a pulley 47, the latter pulley being fast to a vertical shaft 55 upon the lower end of which the knife 9 is mounted. In order to maintain the knives sharp, there are provided grinders 51 and 53 both driven, by mechanism which will

60 now be described, from the step 33. The grinder 53 for the knife 7 is fast to a shaft 55 which is slidably and rotatably mounted

in bearings in the frame of the machine and has a keyway 57 to receive keys carried respectively by pulleys 59 and 61, the latter being driven by a belt 63 which passes around the step 33 and over an idler 65. The grinder 53 is normally held away from the knife 7 by a coiled spring 67 one end of which abuts against part of the frame of the machine and the other against a collar 69 which is fast to the shaft. The position 70 of the grinder is determined by the contact of this collar with a thumb nut 71 threaded on a stationary screw 73. By manipulating the thumb nut the grinder may thus be caused to move into or out of contact with 75 the knife 7. The mounting of the grinder 51 is similar to that of the grinder 53. The shaft 75 which carries the grinder and is inclined as shown, is slidably and rotatably mounted in three stationary bearings 77, 79, 81 and is driven by means of a belt 85 which passes around a pulley 83 on the shaft 75 and around the pulley 59 on the shaft of the other grinder. The pulley 83 is held from longitudinal movement along the shaft 75 by means of a spacer 87. In order to permit the shaft 75 to be adjusted and to be held in adjusted position, a thumb screw 89 threaded upon a stationary screw 91 is located between two outwardly extending ears 93 on a hub 95 which is loose on the shaft 75 and is located between collars 97 and 99 which are fast to the shaft. With this construction it will be clear that when power is applied to the shaft 11 the knives 7 and 9 and the grinders 53, 51 will be rotated continuously; and that the grinders may be moved into operative relation with respect to their respective knives when desired.

Turning now to the knife 7, there is provided a guard 101 which covers all of the edge of the knife except the upper and lower portions and leaves exposed enough of the under side to permit access to the screw 103 by which the knife is fastened to its shaft. This guard is mounted on pins 105 which are adjustably held in sockets in the frame of the machine by set screws 107 so that the guard may be adjusted when desired. In order to guide the toe portion of a shoe in a path which corresponds roughly to the curvature of the knife, there is provided a work guide in the form of three triangularly arranged rollers two of which 109 are at the same level and the other 111 at a lower level.

These rollers are carried by a stem 113 which is slidable in vertically alined bearings 115, said stem being keyed to one of the bearings to prevent it from turning. In order to accomplish vertical adjustment of the stem a thumb screw 117 threaded into the frame of the machine has fast to it a disk 119 which extends into a horizontal

- groove cut in the stem 113. The bearings of the two rollers 109 are rigid with the stem 113, but the bracket 121 which carries the roller 111 is adjustable vertically on the 5 stem and held in position by a set screw 123. The difference in level between the roller 111 and the two rollers 109 can thus be varied to provide for different curves on the bottoms of shoes or lasts of different styles.
- 10 In order properly to support the puckered surplus material as it is being presented to the knife, a guide in the form of a series of fingers 125 is provided. In the illustrative construction there are three pairs of these 15 fingers as best shown in Fig. 4. Each pair is adjustably fastened by a bolt 127 to the downwardly projecting portion of an angle plate 129, the horizontal portion of which is adjustably fastened by cap screws 131 to a 20 supporting plate 133, said last named plate being fast to the lower end of a stem 135 which is vertically adjustable in a bearing in the frame of the machine and held in adjusted position by a set screw 137. After 25 the bolts 127 have been loosened, the fingers may be adjusted up or down, or angularly about the axes of the bolts. The angular adjustment is for the purpose of causing them to conform as nearly as possible to the 30 transverse curvature of the bottom of the shoe. The fingers extend between the puckers and serve in a manner to separate and to support them as shown in Fig. 4. The illustrative machine is designed particularly 35 for operating upon rubber soled footwear such, for example, as arctics, in which the upper material is composed more or less of rubber. In order to keep the edge of the 40 knife wet so as to facilitate cutting rubber or rubberized material, a wick 139 is held against the lower edge of the knife, the lower end of the wick dipping into a reservoir for water as indicated in Fig. 1.
- Referring now to the knife 9 which is 45 designed to trim off surplus material at localities other than the toe portion of the shoe, this knife is also concavo-convex but with the convex side facing downwardly toward the work. Surrounding all of the edge 50 of this knife except the front and back portions is a guard 141 fast to the lower end of a stem 143. Fast to the upper end of this stem is the lower end of an adjusting rod 145 the upper end of which is threaded 55 through a sleeve 147 having at its upper end a thumb nut 149 and fast to its lower end a collar 151 the sleeve being rotatable in a bearing in the frame of the machine but held from vertical movement. By turning 60 the thumb nut 149 the guard 141 may be adjusted vertically. Adjustably fastened to the guard by screws 153 is a gage 155, the screws passing through slots in the gage and being threaded into the guard so as to 65 permit horizontal adjustment of the gage.

This gage, as best shown in Fig. 5, is bent down into a space formed by cutting out a portion of the guard and has a beveled forward edge located in proximity to the edge of the knife. By adjusting the gage away 70 from or toward the edge of the knife, the depth of cut of the knife may be regulated. The purpose of this knife, as has been stated, is to trim off any small projections of surplus material which may be present on the bottom of the shoe aside from that at the toe portion. In the manufacture of certain 75 canvas shoes it is customary to employ a piece of tape 100 which overlaps the vamp and quarter; and in the manufacture of this 80 sort of a shoe, the knife 9 is used to sever the ends of this piece of tape.

The shoe as it comes to the operator of this machine has been lasted, the margin of the upper having been drawn over the insole 85 and attached to the insole by reason of its stickiness. The portion of the upper which overlaps the insole is more or less puckered especially about the toe. It may also be more or less puckered at other points, for 90 example at the shank and it may have a piece of tape 100 the projecting ends of which should be removed. The operator presents the toe of the shoe to the knife 95 as indicated in Figs. 3 and 4 holding the bottom of the shoe against the guide rollers 109 and 111 and pushing the shoe forward. The gage fingers 125 extend between the 100 puckers as shown in Fig. 4. The effective portion of the cutting means 7 conforms approximately to the transverse convexity of the bottom of the shoe and the guiding means comprising the spaced rollers 109 and 111 occupy positions conforming to the longitudinal and transverse curvatures of said 105 bottom, the two rollers 109 preventing side-wise rocking of the shoe so that the knife will not cut more deeply into one margin 110 of the bottom of the shoe than into the other. As the shoe is pushed forward, toe foremost, with the longitudinal middle of the bottom of the shoe in substantial alignment with the middle of the cutting means, the shoe is rocked lengthwise by reason of the difference 115 in level between that of the roller 111 and that of the rollers 109 so that the cutting takes place in a curved path which corresponds substantially to the longitudinal convexity of the bottom of the shoe. The toe of the shoe after having been subjected 120 to the operation of the knife 7 appears somewhat as shown in Fig. 6, all of the puckers around the toe having been cut off. The operator then presents the side of the shoe to the knife 9 as indicated in Fig. 5 and moves the shoe in a curved path such as that indicated by the arrow in that figure in order to cut off the end of the tape or 125 to cut off any pucker which may be present. The margin of the bottom of the shoe is thus 130

made smooth and even so that when a rubber sole is attached and vulcanized to the shoe its bottom will also be smooth.

Although the invention has been described as embodied in a particular machine, it should be understood that the invention is not limited to the particular machine which has been described.

Having thus described my invention, 10 what I claim as new and desire to secure by Letters Patent of the United States is:

1. A machine for cutting off the puckered surplus upper material from the bottom of a shoe having a smooth insole to which the 15 lasted upper is attached by an adhesive substance, having, in combination, a cutter, means for operating the cutter to produce a draw cut, a rigid guide member arranged to engage the bottom of the shoe, and a 20 pucker-engaging member extending over the edge of the cutter.

2. A machine for cutting off the puckered surplus upper material from the bottom of a shoe having a smooth insole to which the 25 lasted upper is attached by an adhesive substance having in combination a rotary disk-like knife and a gage member supported above the knife and extending down over the 30 edge of the knife into contact with the bottom of the shoe.

3. Mechanism for removing surplus material from the bottom of a shoe comprising a concavo-convex knife, means for driving the knife, and a guide adapted to direct 35 the shoe into the concavity of the knife.

4. Mechanism for removing surplus material from the bottom of a shoe comprising a concavo-convex knife, means for driving the knife, and a guide shaped to 40 engage the bottom of the shoe at a plurality of separated points and adapted to direct the shoe to the knife.

5. Mechanism for removing surplus material from the bottom of a shoe comprising a concavo-convex knife, means for driving the knife, and a guide having three 45 triangularly arranged shoe contacting members adapted to direct the shoe to the knife.

6. Mechanism for removing surplus material from the bottom of a shoe comprising a concavo-convex knife, means for driving the knife, and a guide adapted to direct the toe portion of the shoe along the concave side of the knife in proximity thereto 50 to cause the knife to sever the surplus material.

7. Mechanism for removing surplus material from the bottom of a shoe comprising a concavo-convex knife, means for driving the knife, and a guide shaped to engage the bottom of the shoe at a plurality of separated points and adapted to direct the toe portion of the shoe along the concave side 55 of the knife in proximity thereto to cause the knife to sever the surplus material.

8. Mechanism for removing surplus material from the toe portion of a lasted shoe comprising a concavo-convex knife, means for driving the knife, and a guide shaped to direct the toe portion of the shoe to the knife 70 in a path the curvature of which corresponds approximately to that of the knife from a point on the edge to the center thereof.

9. Mechanism for removing surplus upper material from the bottom of the toe portion of a lasted shoe comprising cutting means, and means for guiding the shoe to the cutting means in such manner that the upper material is severed close to the insole, said 75 guiding means including a group of spaced members for engaging separated localities on the bottom of the insole of the shoe.

10. Mechanism for removing surplus material from the bottom of a shoe comprising a knife, and means for guiding the shoe to the knife, said guiding means including spaced rollers located at different levels for 80 engaging separated localities on the bottom of the sole of the shoe.

11. Mechanism for removing surplus upper material from the bottom of the toe portion of a shoe comprising cutting means constructed and arranged to sever surplus material from opposite sides of the shoe simultaneously, and means for guiding the shoe to the cutting means, said guiding means including three triangularly arranged members for engaging the bottom of the insole of the shoe.

12. Mechanism for removing puckered surplus material from the bottom of a lasted shoe comprising a cutter, a guide for directing the shoe to the cutter, and a plurality of members for separating and supporting the puckers.

13. Mechanism for removing puckered surplus material from the bottom of a lasted shoe comprising a cutter, a guide for directing the shoe to the cutter, and a plurality of members arranged to extend between the 110 puckers.

14. Mechanism for removing puckered surplus material from the bottom of a lasted shoe comprising a cutter, a guide for directing the shoe to the cutter, a plurality of members adapted to extend between the puckers, and means whereby said members may be adjusted toward and from the knife.

15. Mechanism for removing puckered surplus material from the bottom of a lasted shoe comprising a cutter having a curved edge and pucker-separating members adjustable to conform to the transverse curvature of the bottom of the shoe.

16. Mechanism for removing surplus material from the toe portion of the bottom of a lasted shoe comprising cutting means the edge of which is inclined in two directions in such manner as to be capable of 120

severing simultaneously the surplus material on opposite sides of the shoe close to the insole, means for operating the cutting means to produce a draw cut, and a guide 5 adapted to facilitate directing of the shoe bottom side up and toe foremost to the cutting means.

17. Mechanism for cutting off the pockers of surplus upper material from the bottom 10 of the toe portion of a lasted shoe comprising rotary cutting means the effective portion of the edge of which is inclined downwardly in opposite directions to provide for the transverse curvature of the bottom of the 15 shoe, and means for guiding the shoe to the cutting means in such manner as to cut off the pockers close to the insole, said guiding means comprising three spaced triangularly arranged members adapted to engage the 20 bottom of the insole, one in advance of the other two.

18. Mechanism for removing surplus material which projects from the bottom of the toe portion of a lasted shoe comprising 25 disk-like cutting means capable of severing simultaneously portions of the surplus material located on opposite sides of the shoe, there being a free and unobstructed space beneath said cutting means to permit the 30 shoe to be presented toe foremost to and past said cutting means with the middle of the bottom of the shoe in substantial alignment with the middle of the cutting means, and means adapted to engage the bottom of 35 the shoe to facilitate such presentation.

19. Mechanism for removing surplus material which projects from the bottom of the toe portion of a lasted shoe comprising cutting means adapted to extend across the 40 bottom of the shoe and shaped to engage simultaneously surplus material located on opposite sides of the bottom of the shoe, and guiding means for facilitating presentation of the shoe bottom side up to the cutting means, said guiding means comprising three members adapted to engage the bottom of the shoe, two of said members being located at the same level and the third being located in advance of the other two and at 45 a different level.

20. Mechanism for removing surplus material which projects from the bottom of a lasted shoe comprising cutting means the effective portion of which conforms approximately to the transverse convexity of the bottom of the shoe, and guiding means adapted to facilitate presentation of the shoe to the cutting means in a curved path which corresponds approximately to the 55 longitudinal curvature of the bottom of the shoe.

21. Mechanism for removing surplus material which projects from the bottom of a

lasted shoe comprising cutting means the effective portion of which extends across the 65 bottom of the shoe so as to engage opposite margins simultaneously and conforms approximately to the transverse convexity of the bottom of the shoe, and guiding means adapted to facilitate presentation of the 70 shoe to the cutting means in a curved path which corresponds approximately to the longitudinal curvature of the bottom of the shoe.

22. Mechanism for removing surplus material from the bottom of a lasted shoe comprising cutting means and guiding means for facilitating movement of the shoe into engagement with the cutting means, said guiding means being constructed and arranged 75 to prevent sidewise rocking of the shoe and to permit and control lengthwise rocking thereof.

23. Mechanism for removing surplus material from the bottom of a lasted shoe comprising cutting means and guiding means for facilitating movement of the shoe into engagement with the cutting means, said guiding means being constructed and arranged 80 to engage the bottom of the shoe at three separate points in such manner as to prevent sidewise rocking of the shoe and to permit and control lengthwise rocking thereof.

24. Mechanism for removing surplus material from the bottom of a lasted shoe comprising cutting means shaped to engage simultaneously opposite margins of the bottom and means constructed and arranged to guide the shoe in such manner that the cut 95 takes place in a curved path which corresponds substantially to the longitudinal curvature of the bottom of the shoe.

25. Mechanism for removing surplus material from the bottom of a lasted shoe comprising cutting means and guiding means constructed and arranged to control presentation of the shoe to the cutting means in such manner as to prevent sidewise rocking of the shoe and to permit and control lengthwise rocking thereof while the surplus material is being severed progressively.

26. Mechanism for removing surplus material from the transversely and longitudinally curved bottom of a lasted shoe comprising cutting means shaped to engage simultaneously opposite margins of the bottom and guiding means arranged to engage the bottom of the shoe at different levels and adapted to cause the path of the cut to curve 115 in accordance with said longitudinal curvature.

In testimony whereof I have signed my name to this specification.

AUGUSTINE FRANK LITTLEFIELD.
